UNITED STATES PATENT OFFICE.

HENRY D. STARR, OF TEXANA, ASSIGNOR TO HIMSELF AND JASPER N. COLE, OF BRYAN, TEXAS.

BALE-TIE BUCKLE.

SPECIFICATION forming part of Letters Patent No. 237,063, dated January 25, 1881.

Application filed September 4, 1880. (Model.)

To all whom it may concern:

Be it known that I, HENRY D. STARR, of Texana, in the county of Jackson and State of Texas, have invented a new and useful Improvement in Bale-Tie Buckles, of which the following is a specification.

Figure 1 is a plan view of the improvement. Fig. 2 is a sectional view of the same, tied. Fig. 3 is a sectional view of the same, partly tied.

The object of this invention is to furnish bale-tie buckles so constructed that the bale can be easily and quickly tied, that will hold the tie securely, and at the same time can be made lighter and neater than ordinary buckles, while having the necessary strength.

The invention consists in constructing a bale-tie buckle of a plate having four transverse slots formed in it, forming five cross-bars, and having the second bar rounded or thickened to adapt the buckle to be hinged to one end of the tie, and having its fourth bar stamped into loop form to receive the other end of the band, as will be hereinafter fully described.

Similar letters of reference indicate corresponding parts.

A represents the buckle, which is formed of a plate of metal having four transverse slots, 1 2 3 4, in it, forming five bars, a b c d e. The 30 bar b, between the slots 1 2, is rounded or thickened, as shown in Figs. 1, 2, and 3, to adapt it to work as a hinge in the looped end of the tie B. The fourth bar, d, is stamped into the form of a loop or keeper, so that the free end of the tie can be readily passed beneath it through the slots 3 4.

When the buckle A is made it is intended that the manufacturer should pass the end of a tie or band, B, through the slots 1 2 and bend it down against the body of the said tie, where

it may be secured in place by a rivet or other suitable means, or may be kept in place by its rigidity. After the tie has been passed around a bale the buckle A is turned so that the other end of the tie B can be passed through the 45 slots 3 4, as shown in Fig. 3. The buckle A is then turned down into its former position, which bends the end of the tie into loop form, as shown in Figs. 1 and 2. With this construction the edges of the buckle A are unbroken, 50 so that the said buckle can be made light and will yet have the requisite strength. With this construction, also, the bale can be easily and quickly tied, and when tied will be held securely.

Having thus fully described my invention, I claim as new and desire to secure by Letters Patent—

1. A bale-tie buckle constructed substantially as herein shown and described, consisting of the plate A, having four transverse slots, 1 2 3 4, formed in it, forming five bars, a b c d e, and having the second bar, b, rounded or thickened and the fourth bar, d, stamped into loop form to adapt it to receive and hold a bale-tie, 65 as set forth.

2. In a bale-tie buckle the combination, with the tie B, of the buckle A, having four cross-slots 1 2 3 4, formed in it, forming five bars, a b c d e, and having the second bar, b, rounded or thickened to hinge the buckle to the tie, and the fourth bar, d, stamped into loop form to receive the free end of the tie, substantially as herein shown and described, whereby the buckle can be quickly applied to the tie and 75 will hold the tie securely.

HENRY DANIEL STARR.
